MODULE FOR A FILTER MEDIA

Joseph N. La Borde, 1801 Ormandy Drive,
Baton Rouge, La. 70808

Filed Mar. 12, 1973, Ser. No. 340,219

Term of patent 14 years

Int. Cl. D23—01

U.S. Cl. D23—4

FIG. 1.

FIG. 2.

FIG. 4.

FIG. 3.

FIG. 1 is a perspective view of a filter media module embodying my new design,

FIG. 2 is a top plan view thereof,

FIG. 3 is a side view thereof, and

FIG. 4 is a cross sectional view taken on line 4—4 of FIG. 3.

I claim:

The ornamental design for a module for a filter media, substantially as shown.
